UNITED STATES PATENT OFFICE.

HARRY M. BROWN, OF NEW KENSINGTON, PENNSYLVANIA.

CAR COUPLING.

Application filed March 7, 1923. Serial No. 623,325.

To all whom it may concern:

Be it known that I, HARRY M. BROWN, residing at New Kensington, in the county of Westmoreland and State of Pennsylvania, 5 a citizen of the United States, have invented or discovered certain new and useful Improvements in Car Couplings, of which improvements the following is a specification.

My invention relates to the construction 10 of a coupler head for cars adapted to be drawn in trains, and, while not so limited, I have developed it in application to cars used for carrying hot metal, slag, etc., in steel-manufacturing plants.

15 In the accompanying drawings Fig. I is a view in elevation, showing fragmentarily the bodies of two adjacent cars coupled together, equipped at their meeting ends and coupled by means of identical coupler heads 20 in which coupler heads my present invention is embodied. In this figure one of the two identical coupler heads is shown in section, on vertical and medial plane. Fig. II is a view of the same assembly, seen in plan 25 from above, and here one coupler head is shown in horizontal and medial plane. Fig. III is a view in vertical section, on the transverse plane indicated by the line III—III, Fig. I.

30 In Letters Patent of the United States No. 1,429,186, granted me September 12, 1922, I have described and claimed certain features of coupler construction, and the coupler head in which my present invention is found 35 is of the general type shown in those Letters Patent.

In the drawings which accompany and form part of this specification the bodies of the two cars coupled together are indicated 40 at 1 and 2. To the sill plates or end timbers of these car bodies the coupler heads are directly bolted. The coupler heads are of bull-nose type, with outwardly flaring open noses, adapted to receive and guide an entering coupling link, and after coupling to allow lateral pivoting of the link within 45 the head. These heads are indicated by the numeral 3. They are provided with laterally extending basal flanges 4, by means of 50 which they may be bolted, as has been said, to the framing of the cars.

A coupling link 5 is shown, uniting the two cars, and it is engaged at either end by a hook 10 of one of the two coupling heads. 55 The hook 10 is pivoted for vertical swing within the head 3 on a pivot admitting of

longitudinal play of hook relative to head, and the hook at its forward end is notched, as at 15, to admit of swing during coupling and of abutment during traction such as 60 to relieve the pivot of traction strain. This matter and the shaping of the anterior and posterior link-engaging faces of hook 10, all of them explained in the specification of my earlier patent, are manifest, and need 65 only be noted here.

As in the coupler head of my earlier patent the space within which the pivoted hook swings is hooded over, indeed it is wholly encased in the boss, or upward extending bay 6, with walls continuous with the walls of the head. This boss affords complete protection to the working parts of the coupler head; spilled or spashed molten metal, falling upon the coupler head, may 70 not gain access, nor may such metal on cooling "freeze" together relatively movable parts.

The hook 10 is engaged from beneath, and preferably at a relatively short interval 80 from its pivot point (which, as has been explained, is, within a narrow range, movable within the head), by a tongue 7 which, carried by the head, extends from beneath through an opening in the nether wall of the 85 head. A rotatable uncoupling rod 8 is provided with a crank bend 9, and this bend, engaging tongue 7, may, when the rod 8 is turned by the manual effort of an attendant, force the tongue upward and in so doing 90 effect upward pivotal swing of hook 10 from coupling to uncoupling position. This tongue preferably takes the form of a strap spring, tending when the hook has been extended, as in traction, to cause it to recede 95 again within its range of play, and so, even though otherwise in locked position, to be ready to be swung to unlocked position without hindrance.

The construction which I now have described admits of being built of minimum depth, in direction of the length of the car, that is to say, of minimum over-all projection from the car frame. The structure may be built, as shown in the drawings, with no extension rearward beyond the pivot point 100 of the coupling link. At that point the structure is, so to say, cut square off, and the lateral flanges 4 are built out, through 105 which the structure may be bolted to the car frame. The tongue 7 of spring steel, secured at its anchored end by a screw 21, ex-

tends downward between the rear face of the structure and the face of the car frame against which it is bolted, and then turning upward extends to engagement from beneath with hook 10, as already explained. The uncoupling rod 8 is suitably journaled in the car frame.

The head being so truncated may be made of a minimum number of parts, easily assembled. The head is open to rearward, as indicated at 22, and through this opening the hook may be introduced and when seated may be secured by application of strap spring 7. Furthermore, the pivot pin 23 on which hook 10 swings may be cast or forged, integral with the hook itself, and make pivotal bearing forwardly upon properly disposed surfaces within recess 22.

I have, in order to afford fullest showing of the coupler head in which my invention is found, shown the meeting ends of two cars to be equipped, both with these heads. This is preferable in the steel-plant use which I primarily contemplate. Manifestly, however, the head in which my invention resides may cooperate with a head of any other type capable of engagement with an ordinary coupling link, such as that indicated at 5.

The coupler head of my present invention is applicable for service in various places and is not limited to steel-plant service, although I primarily contemplate service there.

I claim as my invention:

35 1. A coupler-head of bull-nose type whose upper wall is imperforate and closed against the ingress of any foreign substance, open

rearwardly, and provided within and towards its anterior end with a vertically disposed bearing surface, combined with a hook 40 adapted to be introduced from the rear into the coupler-head and when so introduced under traction adapted to bear upon said strain-sustaining surface.

2. A coupler head of bull-nose type open 45 rearwardly and provided internally with a pivot seat, combined with a hook capable of introduction from the rear to its pivot seat within the head, and a strap spring closing 50 the rear opening and engaging the seated hook and tending to hold it rearward upon its seat.

3. A coupler head of bull-nose type open 55 rearwardly, combined with a hook forwardly notched and rearwardly provided with oppositely extending pivot pins, capable of introduction from the rear into the coupler head and adapted when introduced to engage the body of the coupler head either by its notched forward end or by its pivot-pin bearing rear end, according to its pivotal position, a strap spring 60 engaging the introduced hook and tending to hold it rearward within the coupler head and means for pressing the spring and swinging the hook upwardly from closed to open position.

In testimony whereof I have hereunto set my hand.

HARRY M. BROWN.
